FRACTIONATING TOWER STRIPPER
CONSTRUCTIONJohn S. Wallis, New York, N. Y., assignor to Alco
Products, Incorporated, New York, N. Y., a cor-
poration of Delaware

Application October 31, 1931, Serial No. 572,302

2 Claims. (Cl. 196—139)

My invention relates to a stripper construction for stripping lighter fractions of petroleum hydrocarbons from a fractionating zone in a fractionating tower, and more particularly to a stripper section which is built in and made integral with a fractionating tower.

It has lately become the practice to remove side streams from a fractionating column and strip them of their low boiling constituents, which are present due to the equilibrium which is established between the liquid and the vapor in each fractionating zone. When these lighter fractions are removed it is possible to obtain oils having a higher flash point which are particularly adapted for use in making lubricating oils.

One construction for stripping a side stream in which the stripping section is disposed internally of the fractionating column is shown in United States patent to John W. Lewis, Jr., No. 1,680,421. One disadvantage of the Lewis construction is that the heavy vapors rising in his central cylindrical portion can pass over into the stripping section. When this occurs condensation will take place of these heavy vapors and contaminate the side stream undergoing steam stripping.

One object of my invention is to provide a construction in which a steam stripping means is incorporated in a fractionating tower so that there can be no contamination of the side stream undergoing steam stripping by the heavier vapors.

Another object of my invention is to provide a steam stripper section in which only condensate from one fractionating zone will form the reflux passing through the stripper section.

Other objects of my invention will appear from the following description.

Fig. 1 shows a diagrammatic view of a fractionating column embodying one mode of carrying out my invention.

Fig. 2 is a section taken on the line 2—2, Fig. 1.

Fig. 3 is a view showing a portion of a fractionating tower embodying another mode of carrying out my invention.

Fig. 4 is a section taken on the line 4—4, Fig. 3.

In general, my invention contemplates the establishment of a stripper section within the fractionating column and having no communication with the interior of the column except through a single fractionating stage, from which a portion of the reflux liquid within said stage may pass downwardly into the steam stripper section, wherein the lighter fractions are vola-

tilized and the heavier fractions are withdrawn from the stripper section and passed to overhead cylinder storage, or refluxed back into the fractionating column in order to reduce the partial pressure within the column, while the lighter vapors are stripped and returned to the fractionating zone.

More particularly, referring now to the drawings, Fig. 1 shows the usual fractionating column 1 which may be of any suitable type, having the usual connections 2, 3 and 4 for taking off side streams, and the customary overhead 5 for removing the light fractions. Within the fractionating column are the usual fractionating zones which may be established by bubble trays 6 or in any other suitable manner. The reduced hot crude enters the column through pipe 7, whence it rises into a fractionating zone, as 8 for example. Part of the reflux liquid within said zone 8 will flow downwardly through pipe 9 into the stripper section 10 which is divided into a plurality of zones. Steam enters through pipe 11 into the lower zone 12 of the stripper section. The action of the steam volatilizes the lighter fractions and the vapors rise through bubble trays 13 and 14 and out through vapor riser 16 into fractionating zone 8. The stripped side stream passes out of the stripper section 10 through the line 17 where it may go to overhead cylinder stock or may form a reflux back into the fractionating column. As many stripping sections as may be convenient or desirable may be installed in the various places in the fractionating column, depending upon the number of lubricating oil stocks it is desired to take off.

Thus it is seen that there is no danger of any condensate of vapors of the hot reduced crude entering the tower 1 from going directly into the stripping section.

Fig. 3 shows a modified structure embodied in my invention in which the stripper section is annular rather than segmental, as shown in the modification in Fig. 1. The action in this modification is precisely the same as that described with regard to the structure shown in Fig. 1.

In operation, hot reduced crude is introduced into the fractionating column at any convenient point. Fractionation takes place and the reflux in zone 8 is split so that part of it passes into the stripper section. Steam is introduced into the stripper section to drive off the lighter ends of the fractions and the cylinder stock is withdrawn from the bottom of the stripper section.

It is seen that my construction accomplishes the objects of my invention. I am enabled to produce

a lubricating oil stock which is free of contamination by any of the other fractions within the fractionating column. This will result in a lubricating oil stock of singularly uniform qualities. The 5 discoloration due to contamination by heavy ends will be prevented.

It is to be understood that I do not wish to be limited to the particular form of construction shown and described, except insofar as appears 10 in the following claims.

Having thus described my invention, what I claim is:

1. A fractionating column for processing petroleum hydrocarbons comprising in combination 15 means to establish a plurality of fractionating sections, a stripper section within said column positioned below the lowest of said fractionating sections, and a hot oil inlet pipe to said column below said lowest fractionating section, said stripper section having means to communicate with 20 said lowest fractionating section only, whereby a

lubricating oil stock of uniform quality may be produced.

2. A fractionating column for use in the processing of petroleum hydrocarbons comprising in combination means to establish a plurality of fractionating sections, a stripper section within said column positioned below the bottom-most of said sections, a hot oil inlet pipe to said column below said bottom-most fractionating section, means for introducing steam into the bottom of said stripper section, said stripper section having means to communicate with said bottom-most section only, said means including means for passing reflux liquid from said bottom-most section into said stripper section and means for passing stripped vapor from the stripper section into the bottom-most fractionating section, and means for withdrawing stripped liquid reflux from the stripper section, whereby a lubricating oil stock of uniform quality may be produced.

JOHN S. WALLIS.
